[57] CLAIM

The ornamental design for a sectional waste container, as shown and described.

DESCRIPTION

FIG. 1 is an exploded perspective view of a sectional waste container showing my new design, one of the containers being elevated from the bottom for clarity of illustration;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

FIG. 1

FIG. 6

FIG. 2

FIG. 5

FIG. 7

FIG. 3

FIG. 4
